CLAIM

The ornamental design for a combined camera and light device, as shown and described.

DESCRIPTION

FIG. 1 is a front, left side and top perspective view of a combined camera and light device showing our new design; FIG. 2 is a rear, right side and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict the portions of the combined camera and light device that form no part of the claimed design.
